DESIGN FOR A TOBACCO CAN

Edwin K. Johnson, Munday, Tex.

Application March 6, 1939, Serial No. 83,382

Term of patent 7 years

To all whom it may concern:

Be it known that I, Edwin K. Johnson, a citizen of the United States, residing at Munday, county of Knox, in the State of Texas, have invented a new, original, and ornamental Design for a Tobacco Can, of which the following is a specification, reference being had to the accompanying drawing, forming a part thereof.

Fig. 1 is a rear elevational view of a tobacco can, showing my new design;

Fig. 2 is an edge elevation thereof;

Fig. 3 is a front view; and

Fig. 4 top plan view.

I claim:

The ornamental design for a tobacco can, as shown.

EDWIN K. JOHNSON.
